MACHINE FOR CONDITIONING FEATHERS
AND THE LIKE

Edward R. Frederick, Michael C. Jaskowski, and Martin N. Haller, Pittsburgh, Pa., assignors to the United States of America as represented by the Secretary of the Army

Application June 18, 1953, Serial No. 362,460

13 Claims. (Cl. 34—2)

This invention relates to machines for conditioning 15 landfowl feathers and similar fibrous material to increase their filling power and improve their usefulness as fillers for cold weather garments, comforters, sleeping bags, etc.

For an explanation of the term "filling power," reference may be made to the report entitled "A Proposed Method for Measuring the Filling Power of Down and Feathers" by Henry A. Sinski, publication No. TD 103037, The Office of Technical Services, U. S. Department of Commerce, and to the article by N. B. Edelman in Textile Research Journal, vol 17, p. 199 (1947) entitled "Investigation of Methods for Determining the Filling Power of Feathers." See the Sinski et al. Patent No. 2,706,910 dated April 26, 1955.

The conventional waterfowl down and feather mixture used as a filler for sleeping bags is generally satisfactory, but is much too expensive and is not available in this country in sufficient quantity to satisfy both military and civilian demands. Therefore research has turned to chicken feathers (which chemically are similar to duck and goose feathers and which are available in huge quantities) as probably the least expensive and most promising raw product for making a satisfactory filler. Some of the results of this research are disclosed in the E. R. Frederick Patent No. 2,715,086 dated August 9, 1955, wherein several ways of increasing the filling power of straight and crushed chicken feathers are described. The machine of the present invention is briefly described, but not claimed, in the E. R. Frederick Patent No. 2,714,561, dated August 2, 1955, and is referred to in the E. R. Frederick application Serial No. 287,427, filed May 12, 1952.

The general object of the invention is to provide a satisfactory machine—which may be considered a pilot plant—for the processing of chicken and other landfowl feathers while still wet from treatments (physical and/or chemical) for increasing their filling power and making them acceptable as a relatively inexpensive substitute for the standard waterfowl down and feather mixture. Particular objects are to provide apparatus for feeding, picking, drying, cleaning, sterilizing, fluffing and electrostatically charging landfowl feathers. Other objects will be apparent from the following description taken in connection with the accompanying drawings showing somewhat diagrammatically a preferred embodiment of the apparatus.

In said drawings—

Fig. 1 is a perspective view of the complete apparatus;

Fig. 2 is a side elevation of the same;

Fig. 3 is a top plan view of the same;

Fig. 4 is a vertical section through the feather-feeding mechanism;

Fig. 5 is a vertical section through the feather-feeding mechanism but at right angles to the section plane of Fig. 4, to show the picker in cross section;

Fig. 6 is a fragmentary sectional elevation of a detail of the feather-feeding mechanism;

2

Fig. 7 is a detail in horizontal section through the dust collector; and

Fig. 8 is a vertical section elevation through the machine.

5 The apparatus to be described includes a wet feather feeding and picking unit (shown at the right end of Fig. 1 and at the left end of Fig. 2) arranged to discharge the picked feathers into a closed chamber where the drying, cleaning, sterilizing, fluffing and electrostatic-charging are effected.

Feeding and picking assembly

The feathers, which may be first dry cleaned or laundered to remove dirt, or may be first treated (with or without preliminary cleaning) with magnesium silicofluoride (as disclosed in the E. R. Frederick application Ser. No. 287,427, filed May 12, 1952) or alternatively may be first treated with an alkali metal hydrosulphide (as disclosed in the Frederick and Jaskowski application Ser. No. 343,806, filed March 20, 1953), then are discharged by a conveyer (not shown) while still damp or wet into a hopper 10. Generally the feathers will have about 100% moisture pick-up at this stage. Hopper 10 may be supported on a table 11 and is open on one side to provide a discharge throat 12 through which the damp feathers pass. Feeding of the feathers through throat 12 may be accomplished by an attendant or by a mechanical device (not shown) or by so shaping and constructing the hopper that feeding takes place principally by gravity. For the illustrative apparatus, an attendant is deemed necessary. Immediately adjacent the throat 12 a pair of parallel feed rolls 13, 14 are mounted to rotate on horizontal axes, the bottom roll 13 having longitudinal straight grooves 15 (Fig. 4) preferably about $\frac{1}{32}$ in. deep to give a better grip on and more certain feed of the feathers. The upper roll 14 is smooth. Both rolls are about $\frac{7}{8}$ in. to $\frac{1}{2}$ in. in diameter; the smaller their diameter, the greater the curl imparted to feathers which pass between them. The upper roll 14 has stub shafts or axles 16 which are loosely received in bearing blocks 17, 18 so that the upper roll may move up and down relative to the lower roll 13. An upright or arm 19 is fixed at its lower end to each stub axle 16 and extends through and is slidably in a vertical bore 20 in the corresponding bearing block. Each arm 19 at its upper end is pivotally connected to a lever 21 which has one end pivoted as at 22 upon the top wall of a feed box 23 so as to swing in a vertical plane, and has its outer or free end coupled to a tension coil spring 24, arranged vertically with the lower end of the coil spring attached to the top of table 11. Thus coil springs 24 hold the upper feed roll 14 normally in contact with the lower grooved roll 13; these springs, however, expand to permit clumps of the damp feathers to pass between the rolls.

55 The rolls are driven at about 60 R. P. M. or a little slower by means of a motor 25 (Fig. 2) which drives a reduction gear unit 26 in turn driving a pulley or sprocket 27 about which a belt or sprocket chain 28 is trained. Belt or chain 28 drives a pulley or sprocket 29 fixed to the stub axle 30 of the lower roll 13, as shown in Fig. 4. The upper feed roll 14 is driven from the lower roll occasionally by contact therewith but usually by contact with the feathers which are picked up by the lower roll and forced by it through the pass of the rolls. The spring pressure of the upper roll on the lower is clearly essential for proper drive of the two rolls; also it obviates crushing of the feathers, as the springs will yield before exerting a crushing force on the feathers.

Located adjacent the pass of the feed rolls is a fixed 70 curling bar 31 (Fig. 5) which is a horizontal bar having curved upper and lower edges and a straight or flat face set about one-sixteenth of an inch from the peripheries

of the feed rolls. The width of curling bar 31 (measured vertically) is about equal to the diameter of the feed rolls. All feathers which pass between the feed rolls strike the fixed curling bar and pass between the rolls and the curling bar; in nearly all instances, the feathers pass between the lower roll 13 (which has a fixed axis) and the curling bar, which is an abutment. The effect of this action is to impart a pronounced curl to the feathers. Located just beyond the fixed curling bar 31 is a picker roll 32, which may be a wooden roll having a very large number of coarse nylon or wire bristles or pins 33 sticking out radially; the outside diameter of the picker roll, including the pins, may be $3\frac{1}{4}$ in. to $3\frac{1}{2}$ in. This picker roll is revolved at about 2500 R. P. M. and hence sets up air currents with perhaps a suction, which causes the feathers to be pulled down from the space between the curling bar and feed roll assembly. Cooperating with the picker roll is an inclined wall or chute 34 arranged at an angle of 45° to the horizontal and spaced a short distance from the outer ends of the bristles or pins 33 to provide a throat 35 down which the feathers move. The feathers, curled by their contact with the lower feed roll and the curling bar, are separated by their contact with the bristles or pins 33, so that no clumps of feathers pass down chute 34. Obviously the effect of the picker roll is to push the feathers down the chute as well as pull them down from the curling bar-feed roll assembly. The axis of the picker roll is in the same horizontal plane as the axis of the feed rolls and it is driven at the speed previously mentioned by means of a sprocket chain 36 (Fig. 5) in turn driven by a motor 37 fixed upon table 11 (Figs. 1 and 2). As Fig. 5 clearly shows, the chute 34 is the lower wall of feed box 23. To give access to the interior of the feed box, a hinged door 38 is located in the top of the feed box, permitting the attendant to watch the operation or to reach in to examine the picked feathers, even while the machine is operating.

Also supported on table 11 is a blower 40 driven by another motor 41; the blower has an intake at the bottom of the feed box 23 and has a discharge pipe or tube 42 extending horizontally out from table 11 and leading to the drying and conditioning chamber 50. A damper 43, which is a straight, flat slide valve, is movable horizontally by the attendant to regulate the rate of flow of air and feathers discharged into chamber 50. Damper 43 is preferably held in adjusted position by friction.

Conditioning chamber

The conditioning chamber 50 is an insulated box-like receptacle having an inlet 51 for receiving the damp, picked feathers discharged through pipe 42, said inlet being located in end wall 52 near the lower end thereof. The bottom 53 of chamber 50 supports a steam coil 54 connected to a source of steam (not shown) as a convenient source of heat, or if preferred electric heating coils or natural gas or other heat source may be employed. One of the side walls 55 has a large hinged door 56 (with latching means, not shown) and preferably this door has a glass pane as shown, permitting the operator to observe the operation inside the chamber, which is illuminated. A smaller hinged door 57, also in side wall 55, permits the operator to spray the interior of the chamber so as to treat the feathers as desired without opening the large door 56, which would cause a considerable loss of heat. A second end wall 58, a second side wall 59 and a top wall 60 complete the rectangular chamber.

Mounted on a horizontal shaft 61 journaled in bearings fixed to the side walls 55, 59 is a beater or fluffer 62 which consists of a plurality of straight rigid arms 63 extending radially outwardly from said shaft. A sprocket 64 is fixed to shaft 61 and a chain 65 is trained around sprocket 64 and also around a sprocket 66 fixed to the shaft of a motor 67. This motor is shown as supported by a hanger structure 68 depending from the bottom of the rectangular chamber 50. Preferably several legs 69

support said chamber off the floor and afford the space needed for motor 67 and other parts to be described. The motor 67 preferably has a built-in speed reducer (not shown) or it could be a variable speed motor. Generally the beater or fluffer will operate at a relatively slow speed, about 60 R. P. M. being satisfactory in many cases, although a speed as high as 120 R. P. M. may be attained. The arms 63 may be about 10 in. to 12 in. long and preferably are of stainless steel, as the feathers may have been treated with an acidic or an alkaline solution prior to introduction into the chamber. The lower ends of the beater arms or pins 63 are slightly below the axis of the inlet 51, as shown in Fig. 2, so that the feathers blown in from pipe 42 will encounter the beater arms and be thrown rearwardly and upwardly, sometimes as far as the rear arcuately curved inner wall 70. Inner wall 70 is fixed inside the chamber and is spaced from the end wall 58 to form a generally vertical air passage or duct 71.

Also fixed within the chamber is a false bottom 72 which is supported so as to be spaced above the steam coil 54 to provide another air passageway or duct 73 which extends the entire length of the chamber. The heat from duct 73 is partly conducted through the false bottom 72 to the interior of the chamber. A blower 75 driven by a motor 76 may have an intake (not shown) open to the room in which the machine is located; sometimes the intake for blower 75 is a pipe or conduit 77 which recirculates the air as will be explained later on. The discharge from blower 75 is conducted through a conduit 78 which leads to an opening in end wall 58 at the end of air duct 73. Thus a constant flow of air, indicated by the arrows in Fig. 2, moves over the steam coil 54 or other source of heat, and passes through a reversely bent conduit 79 supported on the end wall 52 below discharge pipe 42, thence through a screen 80 (Fig. 1) fixed across a large opening in end wall 52. A baffle 81 is fixed above screen 80 as shown in Fig. 2 to prevent the heated air blown through said screen from interfering with the desired circulatory motion of the feathers in the chamber; baffle 81 cooperates with the false bottom 72 to hold the hot air current or blast close to the top surface of false bottom 72. As shown, the arcuate rear wall 70 merges with the false bottom 72 so that the air blast will move around the arcuate wall, though with diminished force, and back along the top of the chamber. It will be clear that the revolving beater 62, with its closely spaced arms or pins, augments the air flow, hence the movement of the feathers, from inlet 51 back to the arcuate rear wall 70. When the feathers reach the top of the chamber they will float down toward the beater, to be caught up thereby and circulated again, or else the strong air currents from inlet 51 and conduit 79 will pick up the feathers falling down from the top and will send them back to the rear arcuate wall; this process repeating indefinitely while the machine is in operation. The dampest feathers blown back against the arcuate rear wall may remain there for awhile until they dry out sufficiently to be picked up by the described air currents circulating within the chamber.

The continuous stream of heated air discharged through conduit 79, after rising to the top of the chamber as just described, will find an exit through a screen 82 located in the top wall 60 adjacent end wall 52. Screen 82 has a coarse mesh which will prevent movement of the feathers out of the chamber but will allow dust and feather fragments to pass into a box 83 set on top of the chamber. As shown in Fig. 8, screen 82 is hinged as at 84 to permit feathers to pass up into the box when the screen is swung upwardly after feather-conditioning is completed. A handle (not shown) on the outside of box 83 permits the operator to swing the screen upwardly. Box 83 has an outlet near its top with a suction duct 85 coupled thereto, a slide valve 86 being carried by a pair of sliding rods 87 which hold the valve in adjusted position by frictional contact with the vertical wall of

box 83 through which said rods pass. The operator may push or pull the rods manually from outside the box to bring the valve 86 to the desired position relative to the outlet to open or close suction duct 85. A blower 88 driven by a motor 89 has its intake coupled with suction duct 85, and has its discharge side coupled with a discharge duct 90 discharging to a feather collector (not shown) which may be a porous bag or cage tied on the end of duct 90 to permit collecting of the feathers with concomitant discharge of the air to the atmosphere.

Usually it will be desirable during operation of the machine to withdraw and collect any dust created during the beating operation. This dust may arise from the product added on the feathers before being dumped into the hopper 10, or it may be dirt incompletely removed from the feathers in a prior operation, or it may be a blood product. A suction duct 91 is arranged outside chamber 59, with its intake in box 83 below the intake of suction duct 85, and with a slide valve 92 (like valve 86) to control the suction. Duct 91 extends vertically downwardly to a dust collecting chamber 93 located beneath the chamber. Chamber 93 has a series of fine screen baffles 94 located in staggered relation (Fig. 7) to cause the air flow to move in a tortuous path before leaving the chamber. The interior arrangement of the dust-collecting chamber is only partly shown because the construction is not new, and no claim is made therefor. Also coupled to the dust collector, but on the discharge side, is the suction duct 77 which leads to blower 75 as previously described. A slide valve 95 permits the operator to regulate the suction through duct 77 or to close it entirely, in which case blower 75 will be adjusted to take in atmospheric air. A discharge duct 96 is arranged to discharge the cleaned air flowing out of the duct collector directly to the atmosphere, when this is desired.

As shown in Fig. 2, a damper 100 is hinged adjacent a port 101 in the false bottom 72 below the passageway or duct 71 which is back of the arcuately curved inner wall 70. Damper 100 has a handle with adjusting means (not shown) to hold the damper in the desired position. When damper 100 is closed, all the air blown into the chamber by blower 75 passes over the steam coils or source of heat, but when the damper is partly open, as illustrated, some of the air from the blower will flow up through passageway 71 to the top of the chamber, thence through passage 102 to a screen 103 and through said screen to the interior of the chamber. Damper 100 obviously affords a convenient means for lowering the temperature in the chamber, as the air by-passed by damper 100 through passageway 71 will always be cooler than the air which has passed over the heat source 54.

To turn on or shut off the steam, a valve 104 is provided, and preferably a solenoid-controlled steam valve 105 is also located in the steam line to shut off the steam when the temperature in the chamber becomes too high. Ordinarily a temperature of about 150° F. has been found to be most conducive to proper conditioning of chicken feathers. With this relatively low temperature, recirculating the air as described above will not be practiced. But if the feathers have been impregnated with a resin prior to being fed into the machine, a higher temperature, say about 200° F., may be necessary for proper curing, and in this event the slide valve or damper 95 will be opened to permit blower 75 to take heated air from the dust collector 93, and the discharge duct 96 will be closed to the atmosphere. During treatment of the feathers in the chamber, they will be subjected to an atmosphere of ozone emanating from a pair of ozone lamps 106. An explosion-proof electric lamp 107 is also placed inside the chamber to illuminate the interior.

The several switches for controlling the lamps and motors and the circuits therefor are omitted as being well within the skill of an ordinary mechanic.

Operation

Treated damp feathers from hopper 10 are continuously fed by the feed rolls to the curling bar and picker roll and are curled and picked and the clumps are separated. Then the feathers move down to blower 40 which blows them through inlet 51 to the interior of the chamber. Here the feathers immediately encounter hot air entering the chamber through screen 80 and are carried by this hot air and their own momentum to the revolving beater 62. The beater throws the still damp feathers back against the arcuately curved wall 70. Those feathers which are relatively dry will be moved up along wall 70 and around the top of the chamber and back to the beater again, where they are subjected to further drying and fluffing. The circulation continues indefinitely until the entire feather contents of the chamber appear to be completely dry and highly charged with static electricity. When this condition is attained, the feathers will cling tenaciously to the walls of the chamber (even if the chamber is of metal and is well grounded, as is preferred). The feathers will also cling to the screens 82 and 163 and to the beater arms, in fact to nearly every surface inside the chamber except the glass surfaces of the doors 56 and 57. The operator now raises screen 82 and starts the blower 88, which in conjunction with blower 75 will cause most of the feathers to be sucked out of the chamber and into the bag or other receptacle which collects them. The feathers which remain clinging in the chamber because of their extremely high static charge may be removed by opening door 56 and inserting a vacuum tube (not shown) leading to a vacuum cell; the vacuum tube being passed over the interior surfaces of the conditioning chamber and its working parts to forcibly remove the more obstinately-clinging (i. e., more highly charged) feathers.

We are aware of the Broel Patent No. 1,421,663 dated July 4, 1922, for a machine for handling Kapok, also we have examined the Klayman et al. Patent No. 1,945,296 dated January 30, 1934, for apparatus for cleaning, steaming, sterilizing, drying and fluffing waterfowl feathers used in bedding. Therefore we do not claim broadly a machine for drying and fluffing feathers.

We claim:

1. A machine for drying, fluffing and electrostatically charging wet landfowl feathers comprising, in combination, feather-feeding means; a substantially closed chamber into one end of which the feather-feeding means discharges at a low point in said end; a power-driven beater rotatable about a horizontal axis extending transversely of the closed chamber, said beater having a plurality of radial arms and being so located, proportioned and rotated that said arms during rotating will strike air-borne feathers in the closed chamber and will tend to propel such feathers away from the feathered entrance and up toward the top of the chamber; a source of heat; a blower adapted to pass air over the source of heat; a duct conducting the air so heated into the chamber and discharging said air beneath the feather entrance so that the heated air stream catches the wet feathers and propels them toward said beater; the interior of the chamber having a wall at the rear end opposite to the feather entrance end and curved so that the feathers propelled to the rear by the hot air stream and beater are guided by air currents and said curved wall toward the top of the chamber.

2. A machine for curling, drying, fluffing and electrostatically charging wet landfowl feathers comprising, in combination, a feather hopper; a pair of cooperating feed rolls receiving feathers from the hopper; means for driving one of the feed rolls; a curling bar fixed adjacent the pass of the feed rolls and adapted to be contacted by the feathers as they are discharged by the feed rolls to impart a curl to the feathers; a power-driven picker roll adjacent the curling bar; a power-driven blower; ducts operatively associated with the curling bar and picker so that feathers are carried away therefrom; a substantial-

ly closed feather-conditioning chamber into which the feathers are blown by the blower; means for delivering heated air into said closed chamber; beater means for agitating and fluffing feathers in said chamber, said beater means cooperating with the heated air-delivering means to effect circulation of the feathers in the closed chamber; and a duct for exhausting air from the closed chamber.

3. A machine for drying, cleaning, fluffing and electrostatically charging wet landfowl feathers, comprising, in combination, a substantially closed chamber having two sides, a top, two ends, and a bottom; means for feeding wet feathers into one end of the machine at a low point in said end; blower means for delivering a blast of heated air into the same end of the machine at a point directly below the discharge point of the wet feathers so that the heated air blast picks up the wet feathers; a beater in the closed chamber located directly in the blast of heated air, said beater being rotated by power in such a direction and being so constructed and arranged as to aid in propelling the feathers toward the opposite end of the closed chamber; intermittently operating suction means under the control of the operator connected at the top of the chamber for collecting the feathers after conditioning is completed; and means for collecting dust and fine particles during operation of the beater but before the feather collecting is started, the last-named means including a dust collector below the chamber and a duct leading from the top of the chamber to the dust collector.

4. The invention defined in claim 3, wherein the dust collector has a discharge duct discharging the relatively dust-free air to the atmosphere; and a by-pass duct controlled by a damper is also connected to said discharge duct and to said blower means, so that the warm and relatively clean air discharged from the dust collector may be blown by the blower back into the closed chamber.

5. The invention defined in claim 4, wherein the blower means discharges into a passageway formed by walls directly beneath the closed chamber, a source of heat being located in said passageway, the passageway extending the entire length of the closed chamber and giving up part of its heat by conduction through the wall separating the passageway from the closed chamber.

6. A machine for drying, cleaning, fluffing and electrostatically charging wet landfowl feathers comprising, in combination, pneumatic feather-feeding means; a substantially closed chamber having walls one of which has a feather inlet into which the feather-feeding means discharges; a power-driven beater within the closed chamber, the feather-feeding means blowing the wet feathers against the beater; said beater including a plurality of radial arms revolving in vertical planes and being so located and proportioned as to assist the feather-feeding means in propulsion of the feathers to the wall of the closed chamber which is opposite the feather inlet; a source of heat; a blower discharging air over said source of heat; a duct receiving the heated air and discharging it into the interior of the closed chamber at a level slightly above the bottom of the chamber and adjacent the feather inlet; said last named wall being curved to direct said feathers upwardly to the top of the chamber; a dust-collecting chamber connected with the interior of the closed chamber; and a feather-collecting system intermittently connected with the interior of the closed chamber under the control of the operator.

7. A machine for drying, fluffing and electrostatically charging wet land fowl feathers comprising, in combination, a substantially closed chamber; means including a blower for discharging wet feathers into one end of the closed chamber; a source of heat below the closed chamber within a substantially horizontal air passageway; a blower adapted to blow air through said passageway; a duct adapted to conduct the heated air blown through said passageway into the closed chamber, the discharge point of said duct being adjacent the feather-discharging point; an air passageway at the end of the closed chamber op-

posite to the end where the feathers and heated air are discharged; said last-named air passageway extending generally vertically to the top of the closed chamber and then along the top of the closed chamber and having its discharge at a point intermediate the ends of the closed chamber; and an operator-controlled damper adapted to by-pass part of the air blown into the horizontal air passageway up through said second-named air passageway and into the closed chamber.

8. A machine for drying, fluffing and electrostatically charging wet landfowl feathers comprising, in combination, a substantially closed chamber; means for discharging the wet feathers into the closed chamber; means for agitating the feathers floating in the air within said closed chamber; a source of heat located below the closed chamber within a substantially horizontal air passageway; a blower adapted to blow air through said passageway; a duct delivering the heated air from said passageway to the interior of said closed chamber; a wall within said closed chamber spaced from one end thereof to define a substantially vertical air passageway and a substantially horizontal air passageway at the top of the closed chamber, said vertical and horizontal air passageways communicating with each other; an operator-controlled damper adapted to by-pass part of the air from the blower up into the vertical passageway, thence through the horizontal passageway at the top of the closed chamber; the last-named passageway having a screen to permit discharge of the air so by-passed into the closed chamber.

9. A machine for drying, fluffing and electrostatically charging wet landfowl feathers comprising, in combination, a substantially closed generally rectangular and elongated chamber, means for discharging wet feathers into one end of the chamber; said closed chamber having a false bottom and having air heating means below the false bottom; a blower for blowing air past the air heating means; a duct for conveying the air so heated into the chamber adjacent the point of discharge of the wet feathers; power-driven beater means comprising a plurality of arms fixed to a horizontal rotary member whose axis of rotation extends transversely of the closed chamber, so that the arms rotate in vertical planes parallel to the longitudinal axis of the closed chamber, said arms being in the stream of heated air issuing from said duct and being contacted by the feathers discharged into the closed chamber; means for withdrawing air from the top of the closed chamber; and a duct for delivering the withdrawn air to said blower for recirculation through the machine.

10. A machine for drying, fluffing and electrostatically charging wet landfowl feathers comprising, in combination, a substantially closed chamber; power-driven beater means in said chamber; means including a blower for discharging wet feathers into said chamber and against said beater means; a source of heat; an air duct enclosing said source of heat and having its discharge end in a wall of said closed chamber; a blower adapted to blow air through said duct into said closed chamber; a by-pass for part of the air discharged by said second-named blower, said by-pass taking the air before it has been considerably heated and discharging it into the chamber at a point above the beater means; a damper for controlling or shutting off flow of air through the by-pass; air exhausting means leading from the top of the chamber and including a duct and a movable screen located at the inlet end of said duct to prevent feathers from passing through said duct; a dust-collecting chamber at the lower end of the last-mentioned duct; another duct conveying the clean air from the dust-collecting chamber to the second-named blower; a damper for closing the last-mentioned duct so that the blower receives the air from the atmosphere; and feather-collecting means including a duct coupled to the air exhausting means, and a blower for conveying feathers by suction through the last-named duct after said movable screen has been moved out of the way by the operator.

70

75

11. Mechanism for feeding wet landfowl feathers to a conditioning chamber comprising, in combination, a pair of feed rolls having parallel horizontal axes and arranged one above the other, the lower roll being grooved; means for driving the lower roll; the upper roll being an idler roll having slide bearings and coil springs to cause it to tend to remain in contact with the lower roll, said coil springs permitting the upper roll to rise when a clump of wet feathers passes between the rolls; a horizontally extending feather-curling bar fixed to be closely adjacent the feed rolls on the discharge side thereof, said feather-curling bar presenting a vertical face toward the feed rolls so that feathers moving between the feed rolls will usually strike the vertical face of the curling bar and be bent or curled by contact therewith; a feather picker adjacent the curling bar; and conveying means to convey the feathers away from the space between the feed rolls and the curling bar.

12. The invention defined in claim 11, wherein the picker is a power-driven picker roll rotatable about a horizontal axis and located on the side of the curling bar opposite to that which faces the feed rolls; the picker roll having a multiplicity of flexible bristles or pins sticking out radially and being rotated at high speed so that it pulls the feathers down partly by the air currents set up. 20 25

13. Mechanism for feeding wet landfowl feathers to a conditioning chamber comprising, in combination, a pair of feed rolls extending horizontally and arranged one above the other; the lower roll being grooved; power means for driving the lower roll; the upper roll being a smooth surfaced idler roll held by springs yieldably against the lower roll; both rolls having diameters of about $\frac{1}{2}$ in. to $\frac{3}{8}$ in.; a fixed horizontal feather-curling bar having a straight flat vertical surface spaced about one-sixteenth of an inch from the surfaces of the feed rolls and so located that the feathers as they emerge from the pass of the rolls must encounter said flat vertical surface; means creating a draft to pull feathers down from the space between the rolls and the curling bar; and means to convey the curled feathers away.
